(57) **CLAIM**

The ornamental design for a fire resistant document bag, as shown and described.

DESCRIPTION

FIG. 1 is a front perspective view of the fire resistant document bag of the present invention;

FIG. 2 is rear angled view thereof;

FIG. 3 is a front view thereof;

FIG. 4 is a rear view thereof;

FIG. 5 is a left-side view thereof;

FIG. 6 is a right-side view thereof;

FIG. 7 is a top plan view thereof; and,

FIG. 8 is a bottom plan view thereof.

The stippling in the views is a hook-and-loop material and forms part of the claimed design.
